UNITED STATES PATENT OFFICE.

SARKIS A. CIRKINIAN, OF NEW YORK, N. Y.

DESIGN FOR AN ASH-RECEIVER.

53,029.

Specification for Design.

Patented Mar. 4, 1919.

Application filed December 11, 1918. Serial No. 266,343. Term of patent, 7 years.

To all whom it may concern:

Be it known that I, SARKIS A. CIRKINIAN, a subject of the Sultan of Turkey, residing at New York, in the county and State of New York, have invented a new, original, and ornamental Design for Ash-Receiver, of which the following is a specification, reference being had to the accompanying drawing forming part thereof.

Figure 1 is a plan view of an ash receiver, and

Fig. 2 is an elevation of the same.

I claim:

The ornamental design for an ash receiver, as shown.

SARKIS A. CIRKINIAN.
